CLAIM

The ornamental design for a closure-penetrating support for a bottle, substantially as shown and described.

DESCRIPTION

FIG. 1 is a cross-sectional view, taken on line 1—1 of FIG. 2, of a closure-penetrating support for a bottle, showing my new design. The broken lines representing the water cooling apparatus and water bottle are shown for illustrative purposes only;

FIG. 2 is a top plan view thereof;

FIG. 3 is a bottom plan view thereof; and

FIG. 4 is a top side perspective view thereof with the front wall shown fragmentarily for ease of illustration.
